and in Japan August 4, 1931

10 Claims. (Cl. 179—18)

This invention relates to telephone systems and particularly to improvements in automatic telephone systems.

Its object is to improve and simplify automatic systems in which preferential calls may be made to busy subscribers' lines.

Heretofore systems have been provided in which an operator may set up a connection to a busy line and leave it in such a condition that the line would be automatically seized when the busy condition is removed. Other systems have been provided in which when a calling subscriber's line is connected to a wanted subscriber's line the idle or busy condition of the wanted subscriber's line is tested and the called subscriber when busy notified that another connection with his line is desired. Still other systems have been provided whereby a final switch in the automatic system is so modified that a desired subscriber's line is seized regardless of its busy condition and whereby the usual busy signal is rendered ineffective.

A feature of the present invention resides in means whereby a second calling subscriber may set up a connection to a busy line, receive a busy signal and then by dialing a certain number, for example 1, prepare said connection to ring over the desired subscriber's line and establish the connection to this line when the called subscriber releases the previous connection.

Another feature of this invention is a preferential call arrangement of this kind in which calling subscribers' lines may be connected to a called subscriber's line in the sequence in which the calls are made, a new connection being established as soon as the preceding connection has been released.

Another feature of the invention is a means whereby when a calling subscriber dials the number 1, the busy signal is removed from this subscriber's line provided that no other calling subscriber is awaiting a connection and whereby said busy condition remains in case another calling subscriber is awaiting a connection until this previous calling subscriber has established a connection as the called subscriber's line becomes idle when the busy signal is removed.

Referring now to the drawing, at A is shown a calling subscriber's line in diagrammatic form associated with a connector circuit shown at C in detail. At B is shown a called subscriber's line which terminates at terminals in the bank of connector C and also in terminals at connectors D and E, the brushes of which only are shown.

Descriptions will now be made of a call from subscriber A through connector C to the sub-

scriber B assuming that subscriber B is busy, that is, engaged for example by a calling subscriber through connector D or E, followed by description of the operation of connector C when subscriber B becomes idle and the calling subscriber A made through operations in connector C call subscriber B and be connected for conversation. A description will also be made of the operation of connector C in case the called subscriber B is already engaged by, for example, a connection through connector D and a call has also been extended from a calling subscriber through connector E. In this case connector C will have to wait until the connection through connector D has been released.

If the subscriber A calls, his line is extended in the usual manner through automatic switches over the tip and ring conductors to connector C. A circuit is thereby completed for the operation of relay 10 from battery and ground through its windings, contacts of relay 9 and the calling subscriber's loop over the tip and ring conductor. The operation of relay 10 closes an obvious circuit for the operation of relay 11. When the subscriber A now dials the next digit, relay 10 responds to the impulses thereof and a circuit is closed upon the first release of relay 10 for the operation of vertical magnet 12 and relay 13 as follows: Battery windings of vertical magnet 12 and relay 13 in series, vertical off-normal contacts 14, inner armature and front contact of relay 13, armature and back contact of relay 10 to ground. This causes the operation of relay 13 and vertical magnet 12. When the first step is taken the vertical off-normal contacts 14 change the circuit for relay 13 and magnet 12 to pass through the lower armature and front contact of relay 13. The succeeding impulses cause the vertical magnet 12 to step the brushes of the connector C to the desired vertical position and while these impulses are being transmitted relay 13 which is slow to release remains operated. At the end of this series of impulses relay 13 releases and can not again be operated due to the change in the vertical off-normal contacts 14.

When the last digit is transmitted, the first impulse causes the operation of the rotary magnet 15 and relay 16 from battery in parallel through the lower inner armature and back contact of relay 17, lower inner armature and back contact of relays 18 and 13 in series, vertical off-normal contacts 14, lower armature and front contact of relay 11 and armature and back contact of relay 10 to ground. During the succeed-

ing impulses rotary magnet 15 steps the brushes of the connector C to the desired subscriber's line terminals and while these impulses are being transmitted relay 16 remains operated as it is slow to release.

When the brushes of connector C are connected with the terminals of the called subscriber B whose line is assumed to be busy, a ground will be found on the terminal 20 due to the operation of relay 21. This relay is assumed to be operated while the line of the called subscriber B is engaged. This ground causes the operation of relay 18 before relay 16 has time to release. The circuit may be traced from battery, winding of relay 18, upper inner armature and back contact of relay 17, upper armature and front contact of relay 16, brush S', terminal 20 to ground at the armature and front contact of relay 21. When relay 16 now releases, a locking circuit is established for relay 18 from battery, winding of this relay, upper inner armature and back contact of relay 17, upper make before break contacts of relay 16, upper armature and front contact of relay 18, to ground at the upper armature and front contact of relay 13. Relay 18 in operating closes a circuit from the busy tone source at 22, lower armature and back contact of relay 23, third lower armature and front contact of relay 18, second lower armature and back contact of relay 16, condenser 24 over the ring conductor to the calling subscriber A.

If now the calling subscriber desires to wait for the called subscriber at B to become idle he will dial one impulse and thereby cause relay 10 to be momentarily released. When the ground is applied at the armature and back contact of relay 10, relay 23 is partially operated over a circuit from battery, upper winding of this relay, second lower armature and front contact of relay 18, lower armature and back contact of relay 13, vertical off-normal contacts 14, lower armature and front contact of relay 11, to ground at the armature and back contact of relay 10. This partial operation of relay 23 only causes a connection to be made between the armature and front contact at 25 and when relay 10 again operates a circuit is completed from battery, upper and lower windings of relay 23, contacts 25, second lower armature and back contact of relay 17 to ground at the lower outer armature and front contact of relay 11, thus causing the complete operation of relay 23. Relay 23 in operating completely opens at the lower armature and back contact a connection from the busy tone source 22 to the calling subscriber's line and thus discontinues the busy tone to the subscriber A. The operation of relay 23 also closes a connection to ground for brush S₂ to prepare the circuit of this connector for seizing the called subscriber's line B when it becomes idle. This ground will be applied from the lower outer armature and back contact of relay 17, second upper armature and front contact of relay 23 to brush S₂. The calling subscriber A will now wait until the called subscriber B becomes idle.

When the called subscriber releases the previous connection, the ground is removed from terminal 20. The removal of this ground causes the battery through the cut-off relay 26 to cause the operation of relay 17 over a circuit from battery, winding of cut-off relay 26, terminal 20, brush S₁, upper outer armature and back contact of relay 16, upper winding of relay 17, upper outer armature and front contact of relay 23 to ground at the upper armature and front contact

of relay 11. Relay 17 in operating provides a locking circuit from battery, lower winding and lower second outer armature and front contact of this relay to ground at the lower outer armature and front contact of relay 11. The operation of relay 17 causes the release of relays 18 and 23. Relay 18 in releasing provides a holding circuit for relay 17 to ground at relay 11 at its upper armature and back contact. Relay 23 on releasing opens the connection to the ground at the lower outer armature and back contact of relay 17 so that another waiting connector awaiting a connection to called subscriber B may function to secure a connection to this subscriber when the connection to connector B from subscriber A is released, as will hereinlater be described. The operation of relay 17 now applies ringing current to the called subscriber B from the ringing source 28, upper winding of ringing relay 19 and its upper armature and back contact, upper outer armature and front contact of relay 17 over the tip conductor to the called subscriber's bell and back over the ring conductor, third lower armature and front contact of relay 17 and the second lower armature and back contact of relay 18 to ground. When the called subscriber at B answers the call, relay 19 operates to connect the calling and called subscribers over the tip and ring conductors and conversation between these two subscribers may now begin. Relay 19 is held operated through its lower winding under control of relay 11.

If after the subscriber A has made a call, another subscriber makes a call for subscriber B, this subscriber will be waiting his turn to get a connection to the subscriber B. In this case, the connector through which this connection will be established will receive a ground from the armature and front contact of relay 21 on its terminal corresponding to terminal 20. This causes the relay corresponding to relay 18 to be operated in the same manner as hereinbefore described. It should be observed that in this case the relay corresponding to relay 23 can only be partially operated when the relay corresponding to relay 18 is operated as a result of this second calling subscriber dialing one impulse. This is due to the fact that the lower winding of this relay is short-circuited over a circuit as follows: battery, upper winding of the relay corresponding to relay 23, lower outer armature and front contact of the relay corresponding to relay 18, second upper armature and back contact of the relay corresponding to relay 23, the brush corresponding to brush S₂, to ground supplied over the brush S₁ of connector C as hereinbefore described. This ground on terminal S₂ is maintained until the called subscriber at B becomes idle and relay 23 in releasing removes it. The failure of the relay corresponding to relay 23 to operate fully causes the busy tone on the second connection to remain on the line to the second calling subscriber so that this subscriber will, by the fact that he has dialed one impulse and the busy tone is still remaining on the line, know that the called subscriber is not only busy but that another preferential connection is waiting to be attended to before he can secure a connection to the subscriber B. When the first calling subscriber releases the connection to subscriber B as hereinbefore described the ground on terminal 29 is removed by the release of relay 23. The second calling subscriber's connector will then operate as hereinbefore described to cause the relay corresponding to relay 23 to be fully operated and

remove the busy tone from the line. This indicates to the second calling subscriber that his turn has come to complete the connection to the called subscriber B and the connector circuit for this second subscriber will now function as connector C under the same circumstances as hereinbefore described to complete the connection.

What is claimed is:

1. In a telephone system, a first calling subscriber's line, a second calling subscriber's line, a called subscriber's line, means for establishing a connection between the first calling subscriber's line and the called subscriber's line, means for thereafter partially establishing a connection between the second calling subscriber's line and the called subscriber's line, and means controllable any time before or after the release of the first mentioned connection by the second calling subscriber for completing the second mentioned connection on the release of the first mentioned connection.

2. In a telephone system, a first calling subscriber's line, a second calling subscriber's line, a called subscriber's line, means for establishing a connection between the first calling subscriber's line and the called subscriber's line, means responsive to a certain code signal from the second calling subscriber's line for partially preparing a connection between said second calling subscriber's line and the called subscriber's line, and means for completing said last mentioned connection operative on the release of the first mentioned connection.

3. In a telephone system, a calling subscriber's line, a called subscriber's line, means for partially establishing a connection between said calling subscriber's line and said called subscriber's line if said called subscriber's line is busy and for transmitting a busy tone to the calling subscriber's line, means for transmitting a code signal from said calling subscriber's line over said partially established connection, means responsive to said code signal for removing said busy signal, and means operative when the called subscriber's line becomes idle for completing the partially established connection between said subscriber's line.

4. In a telephone system, a first calling subscriber's line, a second calling subscriber's line, a called subscriber's line, means for establishing a connection between the first calling subscriber's line and the called subscriber's line, means for partially establishing a connection between the second calling subscriber's line and the called subscriber's line, means responsive to the establishing of said partial connection for transmitting a busy tone to the second calling subscriber's line, means for transmitting a code signal from the second calling subscriber's line over said partially established connection, and means responsive to said code signal for removing said busy tone, means thereafter responsive to the release of said first mentioned connection for transmitting ringing current to the called subscriber's line from the partially established connection, and means responsive to the called subscriber answering this ringing by removing his receiver from the hook for completing said partially established connection to the called subscriber's line from the second calling subscriber's line.

5. In a telephone system, a first calling subscriber's line, a second calling subscriber's line, a called subscriber's line, means for establishing a connection between the first calling subscriber's line and the called subscriber's line, means for

partly establishing a connection from the second subscriber's line to line terminals of the called subscriber's line, means responsive to said second connection for transmitting a busy tone to said second calling subscriber's line, means for transmitting from said second calling subscriber's line a current impulse over the partly established connection, means responsive to said impulse for discontinuing the busy tone and for preparing the partially established connection for completion to the called subscriber's line when it becomes idle, means responsive to the called subscriber hanging up his receiver for releasing the connection established from the first calling subscriber and for transmitting ringing current to the called subscriber's line over the terminals to which a connection has been partially prepared from the second calling subscriber's line, and means responsive to the called subscriber answering said ringing by removing his receiver from the switchhook for completing a talking connection between the second calling subscriber's line and the called subscriber's line.

6. In a telephone system, calling subscribers' lines, a called subscriber's line, means for establishing connections from said calling subscriber's lines to said called subscriber's line in sequence in the order in which such attempts are made, a succeeding connection is completed as soon as a preceding one is released, said means being operatively controlled by the individual subscribers making the calls.

7. In a telephone system, calling subscribers' lines, a called subscriber's line, means for establishing connections from said calling subscribers' lines to said called subscriber's line in sequence in the order in which such attempts are made, a succeeding connection being completed as soon as a preceding connection has been released, said means being responsive to signals transmitted from the calling subscribers' lines.

8. In a telephone system, calling subscribers' lines, a called subscriber's line, means for partially establishing connections from said calling subscribers' lines toward the called subscriber's line if said called subscriber's line is busy, and means for completing said connections in the order in which the attempts were made to establish such connections, a connection from a succeeding calling subscriber being completed in response to the release of the connection that has been previously completed in the sequence.

9. In a telephone system, calling subscribers' lines, a called subscriber's line, means for partially establishing a connection between a first calling subscriber's line and the called subscriber's line if the called subscriber's line is busy and for completing said connection when the called subscriber's line becomes idle, means for partially establishing a connection between a second calling subscriber's line and the called subscriber's line while said called subscriber's line is busy due to a connection prior to the first calling subscriber having attempted a connection or due to the first calling subscriber having established the connection to the called subscriber's line, means for transmitting a busy tone to said second calling subscriber's line, means for transmitting a code signal from said second calling subscriber's line over the partially established connection from said second calling subscriber's line, means responsive when said first calling subscriber's line connection has been completed for removing the busy signal to the second calling subscriber's line, and means for

completing the connection from the second calling subscriber's line when the first calling subscriber's connection has been released.

10. In a telephone system, a first calling subscriber's line, a second calling subscriber's line, a called subscriber's line, means for establishing a connection between the first calling subscriber's line and the called subscriber's line, means for thereafter partially establishing a connection

between the second calling subscriber's line and the called subscriber's line, and means responsive to certain code signals from the second calling subscriber's line any time before or after the release of the first mentioned connection for completing the second mentioned connection on the release of the first mentioned connection.
